E. D. & W. H. Gird

Making Ferrules and Rings.

No 63,034.

Patented Mar. 19, 1867.

United States Patent Office.

E. D. AND W. K. GIRD, OF CEDAR LAKE, NEW YORK.

Letters Patent No. 63,034, dated March 19, 1867.

IMPROVED BENDING MACHINE.

The Schedule referred to in these Letters Patent and making part of the same.

TO ALL WHOM IT MAY CONCERN:

Be it known that E. D. GIRD and W. K. GIRD, of Cedar Lake, in the county of Herkimer, and State of New York, have invented a new and improved Bending Machine; and we do hereby declare that the following is a full, clear, and exact description thereof.

Our invention consists in providing a machine by which wood, iron, or other material may be forced into any desired shape.

And to enable others skilled in the art to make and use our invention, we will now proceed to describe its construction and operation, reference being had to the accompanying drawings, forming a part of this specification, and to the letters of reference marked thereon.

Figure 1 is a vertical elevation of one end of the machine showing the bending jaws closed.

Figure 2 is a view of the same end with the jaws open and ready for work.

Figure 3 is a sectional elevation through the line $z z$ of fig. 4.

Figure 4 is a side elevation.

Similar letters of reference indicate like parts.

A is the platform or bed-plate upon which the other parts of the machine rest.

B B are two upright standards, secured at the bottom to the bed-plate A and standing a short distance apart, and connected at the top by a plate. The edges which face each other are straight and parallel, and each has a guide strip or way on its edge, the two forming ways or a guide for cross-heads.

The lower portions of the two uprights B B form a circle, they being wide at that point to allow the jaws $\alpha \alpha$ to be attached. These jaws are segments of circles hung to the outer portion of the circle made by the uprights B B by pivots or bolts upon which they freely play. The inner ends are halved, and when they are open, as in fig. 2, they lap by each other, as seen in the drawing.

The outer ends are cut down on the outside to an edge, leaving the inner portion a circle or a shape to correspond with shape of article bent.

There are two cross-heads which play up and down on the ways. They are placed at each end of a vertical bar, b, or it may be said that the bar is widened at each end, the widened ends having grooves to fit the ways, forming cross-heads. Near the centre of this bar a round disk, C, is attached. The circle of the disk C is about the same diameter as the inside of the jaws $\alpha \alpha$.

C, being attached to the bar b, works up and down with the bar. On the other or inside of this bar a connecting-rod, D, is attached, a wrist-pin being made fast to the upper end of the bar for that purpose. The other end of this connecting-rod is attached to the rim of a fly-wheel, E.

This fly-wheel is fitted to one end of a horizontal shaft, F.

It will be noticed that this fly-wheel has two slots in its rim opposite each other, e e.

The shaft F is supported by stands, G G, which are fast to the platform.

These stands have journal boxes and caps for the journals or bearings of the shaft secured to them in the usual way.

Near the other end of the shaft F there is a spur-wheel, H.

Attached to the stands there is another shaft, J, with a pinion, k, upon one end inside the bearing, and a fast pulley, l, and a loose pulley, m, upon it. The belt drives the machine from the fast pulley l. Still lower down there is a belt-shifter shaft, n, attached to the stands. This shaft has a fork on it to operate on the belt.

As the shaft is moved back and forth the belt is moved from one pulley to the other, either starting or stopping the machine.

This shaft n is moved (endwise only) by a lever, P, which works upon a fulcrum, p, attached to one of the uprights B, (near the top.)

This lever is operated by the rod r, which connects one end with a bell-crank, s. The other end of the bell-crank is attached to the belt-shifter shaft n.

This shaft n is also operated upon by a spring, i, which is continually drawing the shaft towards the rim of the fly-wheel E.

The end of the shaft bears constantly against the side of the rim, except when it enters one or the other of the slots *c c* in the rim.

Attached to the bottom end of the bar *b*, which has the cross-heads upon its ends, and standing at right angles with the bar, there is a pin, *v*. This pin projects from the front or face of the uprights *B B*, about the same as the jaws *a a* do, and of course moves up and down with the bar.

At the left hand, and attached to the left-hand upright *B*, there is an arm, *w*, standing out horizontally, with a long slot through it. In this slot, and arranged to slide back and forth, is a gauge-head, *x*, which can be fastened in the slot wherever desired.

When the jaws *a a* are closed around the disk *C*, as represented in fig. 1, the end of the small belt-shifter shaft *n* is in one of the slots in the rim of the fly-wheel and the belt is on the loose pulley *m*.

Now, to get the machine ready for bending, the attendant pulls down on the rod *r*, which, as before stated, operates upon the bell-crank and upon the shifter-shaft *n*, drawing it endwise out of the slot in the fly-wheel, and at the same time shifting the belt on to the fast or driving pulley *l*. This immediately starts the machine through the pinion *k* and the spur-wheel *H*. The motion of the fly-wheel (by the connecting-rod *D*) throws up the bar *b*, and consequently the disk *C*. The jaws *a a*, being hung loosely to the uprights *B B*, (their pivots being on a line drawn horizontally through the centre of the disk *C*,) the upper ends are raised by the disk and parted, so as to allow the disk to rise up between the parted ends and above them. As the disk rises it leaves the ends of the jaws separated a distance as great as its own diameter, and then ceases to operate upon them; but at this point the pin *v* strikes the lower ends of the jaws, and they being locked or lapped past each other, it carries them up to the position represented in fig. 2.

At this point the fly-wheel has made half a revolution, and the other slot in the rim is brought opposite the end of the shifter-shaft *n*, and that being pressed against the rim, enters the slot at the same moment that it shifts the belt on to the loose pulley, and the machine is stopped short.

The machine is now ready to receive the article or substance to be bent. This piece *y* of wood, iron, or other material, is laid, as represented, horizontally across the ends of the jaws *a a*, with the end of *y* against the gauge *x*, in order to bend the right portion.

The attendant again pulls down the lever *P* by the rod *r*, which both disengages the end of the shaft *n* from the slot in the fly-wheel and shifts the belt on to the driving pulley *l*, at the same moment starting the machine, when the disk descends, forcing down the piece *y* and the jaws *a a* at the same time, till the fly-wheel has made another half revolution, when the disk is raised, as shown in fig. 2. The piece *y* is removed now in the form of a band, and the machine is ready for another operation.

It will be seen that the machine completes the bending process at every revolution of the fly-wheel.

Having thus described our invention, what we claim as new, and desire to secure by Letters Patent, is—

The disk *C* and the jaws *a a*, in combination with the cross-head bar *b*, substantially as described.

We claim the belt-shifter *n*, in combination with the slots *c c* in the fly-wheel and the disk *C*, substantially as and for the purpose herein set forth.

The above specification of our invention signed by us this 22d day of August, 1866.

E. D. GIRD,
W. K. GIRD.
